**STRETCHER PAN FOR ADMINISTERING
INHALATION THERAPY**

Harry L. Davis, Gambrills, and Paul C. Swing, Glen Burnie, Md.; said Davis assignor to the United States of America as represented by the Secretary of the Army

Continuation-in-part of abandoned design application Ser. No. 25,320, Sept. 8, 1970. This application June 14, 1971, Ser. No. 153,130

Term of patent 14 years

Int. Cl. D24—01

U.S. Cl. D83—1 D

*FIG. 1.**FIG. 2.**FIG. 3.**FIG. 4.**FIG. 5.*FIG. 6.

FIG. 1 is a side elevation of a stretcher pan for administering inhalation therapy showing our new design;

FIG. 2 is a top plan view thereof;

FIG. 3 is a side elevation thereof;

FIG. 4 is an end elevation as seen in the direction of line 4-4 of FIG. 1;

FIG. 5 is an end elevation as seen in the direction of line 5-5 of FIG. 1; and

FIG. 6 is a perspective view thereof.

The broken lines are shown for illustrative purposes only.

This is a continuation-in-part of design application Ser. No. D. 25,320, filed Sept. 8, 1970, now abandoned.

We claim:

The ornamental design for a stretcher pan for administering inhalation therapy, substantially as shown and described.
